UNITED STATES PATENT OFFICE.

[JOSEPH W. MICHEL, OF BINGHAMTON, NEW YORK.

DESIGN FOR A CIGAR.

[No. 39,438.

[Specification for Design.

Patented Aug. 4, 1908.

Application filed May 7, 1908. Serial No. 431,520. Term of patent 3½ years.

To all whom it may concern:

Be it known that I, JOSEPH W. MICHEL, a citizen of the United States, residing at Binghamton, in the county of Broome and State of New York, have invented a new, original, and ornamental Design for Cigars, of which the following is a specification.

My invention relates to a new, original and ornamental design for cigars, of which the following is a specification, reference being had to the drawing forming part thereof, which is a perspective view of a cigar showing the design.

The leading or material features of my design consist of the shape or configuration of a

cigar, shaped or fashioned in the form of a Dutch pipe as shown in the drawing, so that in its shape it has the upright stem B, the curved neck F and the rounding bowl A of a Dutch pipe, as shown in the drawing. The stem B is decorated with a fancy cord and tassel C about it, and also with an ornamental band D.

I claim:

The ornamental design for a cigar as shown and described.
